UNITED STATES PATENT OFFICE.

FRANK RUDOLPHI, OF CHICAGO, ILLINOIS, ASSIGNOR TO AMERICAN CAN COMPANY, OF NEW YORK, N. Y., A CORPORATION OF NEW JERSEY.

ROTARY SLITTING-MACHINE FOR CUTTING SHEET-METAL CAN-BODY BLANKS.

No. 801,916.

Specification of Letters Patent.

Patented Oct. 17, 1905.

Application filed March 5, 1904. Serial No. 196,760.

To all whom it may concern:

Be it known that I, FRANK RUDOLPHI, a citizen of the United States, residing at Chicago, in the county of Cook and State of Illinois, have invented a new and useful Improvement in Rotary Slitting-Machines for Cutting Sheet-Metal Can-Body Blanks; of which the following is a specification.

My invention relates to improvements in rotary slitting-machines for cutting sheet-metal can-body blanks or other blanks.

The object of my invention is to provide a rotary slitting-machine for cutting metal sheets into can-body or other blanks of a simple, efficient, and durable construction, by means of which the sheets may be squarely, rapidly, and accurately passed between rotary slitters and subdivided into can-body or other blanks without any tendency to cause

the sheets to buckle or pass askew between the cutters, and by means of which the bur or turned edge produced by each pair of rotary cutters or slitters may be turned both the same way on each blank or in opposite directions at the opposite edges of each blank, and in which the cutters may be readily adjusted.

My invention consists in the means I employ to practically accomplish this object or result as herein shown and described—that is to say, in the novel construction of parts and devices and in the novel combinations of parts and devices herein shown and described.

In the accompanying drawings, forming a part of this specification, Figure 1 is a rear elevation of a rotary slitting-machine embodying my invention. Fig. 2 is a vertical section on line 22 of Fig. 1. Fig. 3 is a detail front elevation, partly in vertical section, showing the cutters arranged for turning the burs in opposite directions on the opposite edges of each blank. Fig. 4 is a similar view showing the cutters arranged for turning the burs in the same direction on both edges of each blank. Fig. 5 is a detail vertical section showing the spring gage or stop for squaring the sheet with the cutters, and Fig. 6 is a detail rear elevation of the same.

In the drawings, A represents the frame of the machine. B B' are the shafts, to which the rotary cutting-disks C C' and feed-rollers D D' are secured. Each of the upper feed-rollers D is provided with a rubber or elastic ring d, fitting in an annular groove d', to give the feed-rollers an elastic grip on the

sheet and cause the same to feed straight and true between the several pairs of rotary slitters.

Each of the lower feed-rollers D' is provided with a reversible metallic tread-ring d², having a shouldered or raised bearing-face d³ at one end, adapted to oppose the elastic bearing-ring d on the upper roller D.

Each of the opposing cutting-disks C C' has a beveled peripheral face c and cutting edge c', the two cutting edges of each pair of upper and lower disks C C' opposing each other. Each of the disks C C' are removably secured to their respective rollers D D', so that by reversing each cutting-disk either of its two opposite faces may be placed adjacent to its roller. Each of the rollers D D' is provided with an annular shoulder or recess d⁴ to receive its cutting-disk C or C'.

The cutting-disks C C' are each removably secured to their respective rollers D D' by screws d⁵. The metallic tread-rings d² on the rollers D' are removably and reversibly secured thereto by screws d⁶, the heads d⁷ of which fit in shouldered recesses d⁸, with which the tread d² is provided at its opposite ends or edges to enable the tread-ring to be reversed, so as to bring the bearing-face d³ opposite the elastic bearing-ring d on the upper roller D whether the cutting-disks C C' be arranged as shown in Fig. 3 or in the reverse arrangement shown in Fig. 4. The rollers D' are adjustably fixed to the shafts B B' in different positions, as may be required, by set-pins d⁹ and tight-fitting friction-plugs d¹⁰, having cam-faces d¹¹ bearing against the pins d⁹ and furnished with square heads d¹² for turning the same.

F is the feed-table, the same being furnished with a reciprocating feed-slide F', which is connected by a link f with an arm f' on a rock-shaft f², having an arm f³, connected by a link f⁴ with a crank-arm f⁶, on the shaft B of the upper cutter C and roller D.

G is an inclined guard-plate having a curved foot g, under which the sheet is pushed over the feed-table F into the bite of the feed-rollers D D' and cutting-disks C C', the inner edge of the feed-table and of this inclined guard G projecting toward and near the rollers and cutters. To square the front edge of the sheet with the cutters and cause the sheet to feed truly and properly into the cutters and feed-rollers with its front edge parallel

2 to the axes of the cutter-shafts B B', I provide the inclined guard-plate G with a plurality of pivotal spring-actuated sheet-squaring guards or devices g' , the same being pivoted or hinged at g^2 to ears or lugs g^3 on the inclined guard-plate G, and yieldingly held in position by springs g^4 . The forward movement of the sheet itself lifts or pushes the pivotal spring-actuated squaring-guard g' out of the way as the sheet passes into the bite of the feed-rollers D D' and cutters C C'. The hinged sheet-squaring gages or devices g' stop or retard the sheet as it is fed forward by the feed-gage F' and causes the rear edge of the sheet to bear snugly and squarely against the feed-gage F' at the time it enters the bite of the rollers D D' and cutters C C'.

By combining with the shafts and feed-rollers thereon reversible cutting-disks removably secured thereto and reversible tread-rings reversibly secured to the rollers on one of the shafts I am not only enabled to turn the burs both in the same direction or in opposite directions, as may be desired, but I am also enabled to subdivide the sheet into narrow strips or blanks by the rotary cutters, as in the arrangement shown in Fig. 4. The narrow space between adjacent slits or cuts only equals the thickness of one cutting-disk and its roller.

30 As in my invention the rollers on one shaft are furnished with metallic tread-rings, while those on the other shaft are furnished with rubber or elastic tread-rings, the bearing-surface of the metal tread-rings may be always maintained on a level or proper relation with the cutting edge of the cutting-disks, and consequently all danger of buckling the sheet or

causing it to pass askew, incident to the use of elastic tread-rings on both upper and lower rollers, is avoided, while at the same time I 40 secure the requisite elastic grip on the sheet by reason of the rubber tread-rings on the rollers of one shaft.

I claim—

1. In a rotary sheet-metal-slitting machine 45 the combination with upper and lower rotating shafts, of rollers and cutting-disks on said shafts, the rollers on one of said shafts having elastic bearing-rings, and the rollers on the other shaft having reversible metal tread- 50 rings, substantially as specified.
2. In a rotary sheet-metal-slitting machine the combination with upper and lower rotating shafts, of rollers and cut-disks on said shafts, the rollers on one of said shafts having elastic bearing-rings, and the rollers on the other shaft having reversible metal tread- 55 rings furnished each with a raised bearing-face, substantially as specified.
3. In a rotary sheet-metal-slitting machine 60 the combination with a pair of shafts, of rollers having elastic bearing-rings on one of said shafts, rollers having removable and reversible tread-rings on the other shaft, and reversible cutting-disks removably secured to said 65 rollers on said shafts, whereby the burs may be turned the same way, or turned in opposite directions, as desired, substantially as specified.

FRANK RUDOLPHI.
